M. V. VENTRELLA

AUTOMATIC MUSIC SHEET TURNER

Filed May 29, 1925

FIG. 1

十一

11

五
6

INVENTOR

Michael V. Ventrella
BY ATTORNEY

UNITED STATES PATENT OFFICE.

MICHAEL V. VENTRELLA, OF BRONX, NEW YORK.

AUTOMATIC MUSIC-SHEET TURNER.

Application filed May 29, 1925. Serial No. 33,617.

This application is directed to the same subject matter as my co-pending application, Serial Number 33,618, filed May 29, 1925 for automatic leaf turner.

5 This invention relates to improvements in music leaf turners, particularly turners for the leaves of sheet music and it is the principal object of the invention to provide a device of this character in which a cam 10 controlled and foot operated finger engages special pockets attached to the music sheets while a spring carries the finger back into its original position, thus taking the sheet of music, the pocket of which is engaged by 15 said finger, along to turn the sheet.

Another object of the invention is the provision of a novel means for attaching the pocket carrying frame to the sheet of music.

20 A further object of the invention is the provision of a sheet music leaf turner provided with means for making its operation positively noiseless.

A still further object of the invention is 25 the provision of a sheet music leaf turner allowing an adjustment to the size of sheet and to the requirements for operating the pocket engaging finger.

These and other objects of my invention 30 will become more fully apparent as the description thereof proceeds, and will then be more specifically defined in the appended claims.

In the accompanying drawing forming a 35 material part of this disclosure:

Fig. 1 is a front view of a music stand equipped with a leaf turner constructed according to my invention.

Fig. 2 is a side elevation thereof.

40 Fig. 3 is an enlarged detail view of the cam housing and drum therein to which a finger adapted to turn the leaves is attached.

Fig. 4 is a sectional detail view of the cam housing seen in the direction of arrows 45 4-4, Figure 5.

Fig. 5 is a top plan view seen in the direction of the arrow 5-5 of Figure 4.

Fig. 6 is a rear view of the music-leaf support, seen in the direction of arrows 50 6-6 of Figure 2.

Fig. 7 is a top plan view of a weighted pedal or treadle.

Fig. 8 is a section on line 8-8 of Figure 7.

55 Fig. 9 is an enlarged detail front elevation of the pockets formed with the music

sheets and means for attaching the same to said sheets.

The leaf turner is mounted on the customary hollow music stand 10 having collapsible legs 11 and foldable links 12 connected to the legs and to a sliding collar 13 on the stand.

A rod 14 is vertically displaceable within stand 10 and adapted to be held in any of 65 its extended positions from said stand by means of the usual wingscrew 15.

This rod 14 carries the customary foldable table or support 16 for the sheets of music 17 supported at their lower ends on 70 the customary projecting flange 18.

All these parts so far described, are of ordinary well known construction and form no part of this invention.

In rear of the support the rod 14 carries 75 a plate 19 having elongated notches 20 in its upper edge and openings 21, 22 and 23 with elongated slots formed therewith for the reception of suitable buttons 24, 25 and 26, or the like, on the support adapted to slide 80 into the elongated slots for firmly holding said plate 19 on the support.

Similar buttons 27, or the like, of an upper holder 28 enter the notches 20 to hold the same in its relative adjusted position to 85 the plate 19. The holder has a forwardly projecting flange 29 on which rest the lower edges of a card-board or the like frame including, bars 30, foldable in the center part, one for each sheet of music which have 90 their ends formed into sleeves 31 and 32 respectively, through which substantially vertically arranged card-board bars or the like, 33, 34 pass, the lower ends of which are attached by means of staples 35, or the 95 like, passed through elements 36, and the sheet of music, in order to secure bars 33, and 34 to the upper edges of the music sheets 17.

At the front faces of the frame bars 30, 100 pockets 37 are formed therewith or fastened thereto by means of glue, etc.

These pockets are adapted to be engaged by an operating finger 38 jointed as at 39, to a link 40, secured as at 41, to a drum 42 105 within a housing 43 having an opening formed with a cam face 44. Within the drum a spiral spring 45 is provided having one of its ends secured to a central pin 46 while its other end is attached to a boss of 110 the drum. A spring 47 has one of its ends guided about part 40 and the other engaging

the top edge of operating finger 38. A cable 48 is guided about the drum 42 and secured thereto at one end, as at 49, and is guided over a roller 50 in an opening of the housing 5 and a roller 51 journaled in a nose 52 of plate 19.

To the lower end of said cable the upper end of a cable or chain 53 is secured, adapted to be shortened and lengthened as indicated at 54, an having its lower end connected to an operating rod 55 secured to an eye 56 of a treadle or pedal 57 weighted as at 58, and having its rear end pivoted to a frame 59 padded as at 60, while a similar pad 61 is attached to the lower face of the pedal oppositely disposed to pad 60 in order to make the operation of the foot pedal noiseless. The frame 59 has a U-shaped front part 62 limiting the upward movement of the pedal.

The weight 58 is for the purpose of making the weight of foot pedal 57 to equalize the strength of spring 45 and thus to allow finger 38 and the music sheet to stay in any desired position.

The device operates as follows:—

Upon the proper adjustment of the chain 53 and 54 to suit the height of the music stand, the pedal is depressed on the front portion to operate the drum which will swing finger 38, as the link 40 to which it is attached guides along the cam face 44 in position above the pocket 37. If now the pedal is depressed on the rear portion, the spring 45 will act to carry the finger back into its original position while its link is gliding along the cam face 44 to the lower part thereof, allowing the finger 38 to engage in the pocket 37 and carry the music sheet with the pocket which it engaged, into this position.

It is to be understood that although I have referred to music sheets, book pages or any other sheets may be turned by my device. Pockets 37 of appropriate size, may be readily attached to a sheet of corresponding size by the musician or any one who wants to use the sheet turner.

My music stand may be of any height and

may be placed on the floor or on a piano 50 with a suitable extension for foot pedal 57.

A co-application for Letters Patent using my leaf turner device for books especially is filed simultaneously with this application.

It will be also understood, that while I 55 have shown and described one form of my invention as an example, the same may be subjected to many changes in its general arrangement and construction of the minor details, as fall within the scope of the appended claims without departure from the principle involved.

Having thus described my invention, what I claim as new, and desire to secure by Letters Patent, is:

1. In a music sheet turner, a sheet holder with associated fastening means, comprising a plurality of frame bars foldable at the center, one of said frame bars being formed with notches for fastening to a support by 70 engaging buttons on said support, the front faces of each of the other frame bars being formed with pockets, sleeves formed near the outer edges of said frame bars, and vertically arranged bars slidable in said sleeves, 75 the lower ends of said vertically arranged bars being formed with sheet gripping means.

2. In a music sheet turner, a sheet holder with associated fastening means comprising a plurality of adjacently positioned frame bars foldable at the center, the rear one of said frame bars being formed with means for fastening to a support, the front faces of each of the other frame bars being formed with pockets, sleeves formed near the outer edges of said frame bars, and vertically arranged bars slidable in said sleeves, the lower ends of said vertically arranged bars being formed with sheet gripping means, 80 whereby each vertically arranged bar may be individually adjusted to accommodate sheets of different heights resting with their lower edges on the same support base.

In testimony whereof I have affixed my 85 signature.

MICHAEL V. VENTRELLA.
